UNITED STATES PATENT OFFICE.

WILLIAM ALFONSO LIGHTHEART, OF HAMILTON, ONTARIO, CANADA, ASSIGNOR OF
ONE-HALF TO GEORGE R. HARVEY, OF HAMILTON, ONTARIO, CANADA.

DUMB-WAITER.

1,127,462.

Specification of Letters Patent.

Patented Feb. 9, 1915.

Application filed December 20, 1912. Serial No. 737,358.

To all whom it may concern:

Be it known that I, WILLIAM ALFONSO LIGHTHEART, of the city of Hamilton, in the county of Wentworth, in the Province of Ontario, Canada, manufacturer, having invented certain new and useful Improvements in Dumb-Waiters, do hereby declare that the following is a full, clear, and exact description of the same.

10 My invention relates to improvements in dumbwaiters and the object of the invention is to devise a dumbwaiter which is suspended from the joists of the upper floor and which will extend down below the same but 15 will be clear of the floor below.

A further object is to devise means for locking the waiter portion in a closed or down position, so that the top of the same will be flush with the floor above; and a 20 further object is to provide means actuated by a handle on the top of the waiter portion for releasing the lock.

The invention consists of a jamb portion having a suitable door therein below the 25 joists, a metal frame secured to the top of the jamb and designed to be counter-sunk into a suitable opening in the upper floor above, the waiter portion having suitable shelves therein and vertically slidable within 30 the jamb portion, cords extending over pulleys secured to the jamb portion and secured at one end near the bottom of the waiter portion, the other ends of the cords being provided with suitable weights for counter 35 balancing the weight of the waiter portion, a lock counter-sunk into the top of the waiter portion having a suitable bolt designed to be held by a spring into the slot in the jamb when the waiter is in the closed or down 40 position, a handle pivotally connected to the top of the waiter portion and having depending pronged portions designed to engage the bolt and to release the same when the handle is turned into a vertical position 45 all as hereinafter more particularly described and illustrated in the accompanying drawing in which:

Figure 1 is a front elevation of my device showing the upper part in section. Fig. 50 2 is a vertical section thereof. Fig. 3 is a cross section. Fig. 4 is a section of the upper part of the waiter portion showing the lock and handle applied thereto. Fig. 5 is a perspective detail of the handle. Fig. 6 is a 55 perspective detail of the bolt of the lock.

Like characters of reference indicate corresponding parts in different views.

1 is the jamb of the dumbwaiter and 2 is the metal frame suitably secured to the top and designed to be set into an aperture in 60 the upper floor 3 so that the upper edge of the same is flush with the surface of the floor. The metal frame 2 is suitably secured to the jamb 1 of the dumbwaiter by the pins 2^a; consequently when the metal frame is in 65 position on the jamb the same will be supported or suspended from the upper floor 3.

3^a is the lower floor.

4 are the joists upon which the floor 3 and the jamb portion are supported. 70

5 is the door of the jamb portion having a suitable screened front 6.

7 is the waiter portion vertically slidable in the jamb portion and having vertical grooves 8 in the sides thereof into which 75 guides 9 secured to the inner sides of the jamb portion extend.

10 are suitable pulleys secured to the jamb portion, 11 are cords extending around the same and down the grooves 12 in the sides of the waiter portion; said cords being secured at one end near the bottom of the waiter portion and the other ends being provided with counter balancing weights 13. 80

14 are the shelves of the waiter portion. 85

15 is the lock suitably inserted into the top of the waiter portion and having a bolt 16 adapted to enter a slot 17 in the jamb portion 1 when the waiter portion is in the down or closed position. 90

18 is a cross bar provided on the inner end of the bolt 16.

19 is a handle pivotally connected in a frame 20 which is counter-sunk into the top of the waiter portion. 95

19^a are depending prong shaped portions adapted to engage the cross bar 18 releasing the bolt when the handle is raised into a vertical position. The bolt is held in engagement with the slot by a spring 21. 100

From the above description it will be seen that when it is desired to raise the waiter portion it is only necessary to pull up the handle 19 which releases the bolt 16 and allows the waiter portion to be drawn upward to a requisite extent. When the waiter is done with it is simply pushed down until the top of the waiter portion is flush with the floor when the spring 21 forces the bolt 16 into the slot 17 of the jamb; further the 110

dumbwaiter being supported on the joists will not be affected by the settling of the house or the warping as would otherwise occur, as it is freely supported from the 5 said joists. Also it is to be understood that the dumbwaiter does not extend down as far as the floor below. For instance assuming that it is desired to place the waiter between the cellar and the floor of the kitchen 10 it is supported from the joists of the kitchen floor and the jamb extends down into the cellar, but it is clear from the cellar floor. This prevents any vermin getting into the waiter.

15 What I do claim as my invention, and desire to secure by Letters Patent, is:—

A dumbwaiter, comprising a jamb portion, a metal frame suitably secured to the top of the jamb portion, said metal frame 20 also secured to the upper floor and support-

ing the jamb portion, said jamb portion being clear of the lower floor, a waiter portion vertically slideable in the jamb portion, said waiter portion having vertical grooves in the side thereof, guides secured to the jamb 25 portion and fitting in said grooves, pulleys journaled to the jamb portion, cords extending over the pulleys, one end of each secured to the waiter portion near the bottom of the same, counter-balancing weights attached to 30 the free end of each cord, and means for locking the waiter in the down or closed position.

In witness whereof I have hereunto set my hand in the presence of two witnesses.

WILLIAM ALFONSO LIGHTHEART.
